S. Webster
ATTORNEY

UNITED STATES PATENT OFFICE.

LLOYD W. BUCHENAU, OF STOCKTON, CALIFORNIA.

GUM AND MINT CASE.

1,349,263.

Specification of Letters Patent.

Patented Aug. 10, 1920.

Application filed June 28, 1918. Serial No. 242,382.

To all whom it may concern:

Be it known that I, LLOYD W. BUCHENAU, a citizen of the United States of America, residing at Stockton, in the county of San Joaquin and State of California, have invented certain new and useful Improvements in Gum and Mint Cases; and I do declare the following to be a clear, full, and exact description of the same, reference being had 10 to the accompanying drawings, and to the characters of reference marked thereon, which form a part of this application.

This invention relates to improvements in show cases and particularly to that type of 15 small portable case designed to stand on the permanent or stationary show tables or cases for the display and sale of packages of chewing gum, mints, and similar small confections, the features embodied herein being in 20 addition to the construction as described and claimed in my application for patent for gum and mint case, filed March 11, 1918, Serial No. 221,682.

Confections of the kind stated above dry 25 out and become stale very rapidly when taken from their shipping boxes and exposed to the hot, dry air of summer, and so become unsaleable, and a certain percentage of the merchant's stock is left on his hands if he 30 exposes it in the ordinary show-cases for any length of time.

With this fact in mind, I have so constructed my show-case that the same becomes 35 in effect a humidor thereby retaining the freshness of the articles placed therein. Other novel features are also embodied in this application, thereby providing a case which is inexpensive to construct yet exceeding practical for the purpose for which 40 it is designed.

These objects, I accomplish by means of such structure and relative arrangement of the parts as will fully appear by a perusal of the following specification and claim.

45 On the drawings, similar characters of reference indicate corresponding parts in the several views.

Figure 1 is a side view of my improved case, showing the body portion in section, 50 and with one of the lids raised.

Fig. 2 is a top plan view of the same, one of the lids being thrown back.

Fig. 3 is a fragmentary top plan showing a hinging means.

55 Fig. 4 is a section taken on a line Y—Y of Fig. 3.

Referring now more particularly to the figures of reference in the drawings, 1 represents the stand or pedestal of the case on which is rotatably mounted a polygonal- 60 edged bottom plate or base 2 having vertical posts 3 secured at each corner thereof, each of said posts being grooved on each side to receive and hold glass side-walls 4 of the same height as the posts 3 following the con- 65 tour of the base 2.

Diametrically secured to and between any two of the posts 3 is a division wall 5, the center line of which is also the abutting line of the end members 6 of two covers or lids 7 70 positioned back to back, the outer frames 8 thereof resting when the lid is closed on the tops of posts 3 and side walls 4. The frame pieces 6 and 8 are grooved on their inner edges for the reception of glass plates 9, the 75 frames 6 being built up of two thicknesses of material laid one on the other and normally sprung slightly apart, their parting line being at the level of the glass 9. The two sections are held together by suitably 80 spaced screws 10. This construction enables me to slip the cover-glasses 9 out for replacement by merely removing the screws 10 and possibly one of the screws of each of the hinges hereinafter described. 85

At each end of the frames 6 is a hinge 11 secured centrally to both of the frames 6, the usual hinge-pin being replaced by an inverted U-shaped hinge pin 12 which is driven down into the division wall 5 and the posts 90 3 connected thereto.

With this construction, it is possible to raise each lid and lay it over on the other without the necessity of having a center piece to screw the hinges to and with the use of 95 only two hinges.

Centrally located on the base is a center post 13, from which, equally spaced around, division walls 14 radiate to each of the edge posts 3, the top level of the post 13 and the 100 walls 14 being slightly lower than that of the outer walls and posts.

The post 13 is bored out from the top to a suitable depth to receive and seat a metal cup 15 adapted to contain a sponge or similar article and a small amount of water. With this construction, it will be evident that the moisture emanating from the cup will permeate to all the compartments of the case. By raising both lids at once, the 110 sponge is readily removable.

From the foregoing description, it will

readily be seen that I have produced such a device as substantially fulfills the objects of the invention as set forth herein.

While this specification sets forth in detail the present and preferred construction of the device, still in practice, such deviations from such detail may be resorted to as do not form a departure from the spirit of the invention, as defined by the appended claim.

Having thus described my invention, what I claim as new and useful and desire to secure by Letters Patent is:—

In a show case having a base, and side

walls thereon, a transverse division wall, a 15 pair of lids disposed back to back along the center line of the division wall, hinges connecting the lids and a common U-shaped hinge pin mounted to each hinge centrally thereof and being driven into the division 20 wall and passing between the abutting edges of the lids.

In testimony whereof I affix my signature in presence of two witnesses.

LLOYD W. BUCHENAU.

Witnesses:

VERADINE WARNER,

BERNARD PIUAT.
